United States Patent Office

Des. 175,508

Patented Sept. 6, 1955

175,508

CHARM BRACELET OR THE LIKE

Adolph Katz, Providence, R. I., assignor to Eastern Jewelry Mfg. Co. Inc., New York, N. Y., a corporation of New York

Application March 8, 1955, Serial No. 34,922

Term of patent 7 years

(Cl. D45—4)

Fig. 1

Fig. 2

Fig. 3

Fig. 1 is a front elevation view of a charm bracelet or the like showing my new design.

Fig. 2 is an edge view of the charm portion.

Fig. 3 is a rear view of the charm portion of Fig. 1.

The dominant feature of my design resides in the portion shown in solid lines.

I claim:

The ornamental design for a charm bracelet or the like, substantially as shown and described.
